UNITED STATES PATENT OFFICE.

CHARLES O. MICHAELSEN, OF OMAHA, NEBRASKA, ASSIGNOR TO MINNIE E. MICHAELSEN, OF MINNEAPOLIS, MINNESOTA.

ORE-PULVERIZER.

1,247,701.

Specification of Letters Patent. Patented Nov. 27, 1917.

Application filed October 24, 1914. Serial No. 868,511.

To all whom it may concern:

Be it known that I, CHARLES O. MICHAELSEN, a citizen of the United States, and a resident of Omaha, in the county of Douglas and State of Nebraska, have invented certain new and useful Improvements in Ore-Pulverizers, of which the following is a specification.

My invention relates to grinding and pulverizing machinery, and especially to machines for fine-grinding or pulverizing of ores preparatory to concentration, or separation therefrom of the valuable metalliferous constituents thereof. It is the object of my invention to provide a grinding or pulverizing machine wherein the final reduction of the material is effected by a rubbing and rolling of its particles between a pair of plates having parallel grinding or rubbing surfaces, the said plates being actuated so as to have a composite movement during which their adjacent surfaces move alternately toward and away from each other by very slight amounts, and also move to a much greater extent in directions parallel to each other, but oppositely and in alternating directions; so that the material between the plates is subjected to a moderate pressure insufficient to crush the same by direct compression thereof, and while under said moderate pressure is rolled or rubbed between the plates so as to be disintegrated largely by the abrasive action of its particles upon each other. A further object of my invention is to provide, in connection with the rubbing plates, means for constantly feeding materials into the space between the same, and means for causing the reduced material to be ejected therefrom at a rate proportional to the feeding and reduction thereof. A further object of my invention is to provide actuating mechanism for the pulverizing devices, arranged so that the rate of movement of the primary driving member is inversely proportional to the force or intensity of pressure that must be exerted by the pulverizing devices at any instant, whereby the actuating force required for operating the machine will be substantially uniform. Further and more specific objects of my invention will appear hereinafter.

In the accompanying drawings, Figure 1 is a longitudinal vertical sectional view of a machine embodying my invention, the sec-

tion being in the plane of the line $x-x$ of Fig. 3, Fig. 2 is a side view of the machine, with the adjacent fly-wheel removed, Fig. 3 is a partial plan view of the machine, and partially a horizontal section on the plane 60 of the line $y-y$ of Fig. 2, Fig. 4 is a detail vertical sectional view, illustrating the action of the pulverizing devices, Fig. 5 is a side view showing the same parts in a different position, Fig. 6 is a detail vertical section on the plane of the line $z-z$ of Fig. 2, Fig. 7 is a detail horizontal section on the plane of the line $o-o$ of Fig. 1, and Fig. 8 is a diagrammatic view of the rocking-beams, illustrating the relative movements 70 of the working-faces.

In carrying out my invention I employ a pair of rocking-beams mounted to oscillate about normally-fixed axes, and connected with each other so as to move simultaneously 75 in like direction and through equal angles about said fixed axes. In the structure illustrated, there is a front rocking-beam 1 and a rear rocking-beam 2, which are mounted respectively on horizontal shafts 3 and 4, of 80 which the axes are parallel and lie in the same horizontal plane. Through the lower portions of the beams and at like distances from the respective shafts 3 and 4 are the link-shafts 5 and 6, of which the axes also 85 lie in the same horizontal plane. The rocking-beams are disposed between the side-members 7 of a suitable frame. The frame side-members 7 are connected to each other at the rear end by a cross-piece 8 secured 90 thereto by transverse bolts 9. At the front end of the frame there is an upper cross-piece 10 secured to the side-members by large studs 11 and nuts 12, and a lower cross-piece 13 which is secured to the side-members by studs 14 and nuts 15.

The end-portions of the pivot-shaft 4 of the rear rocking-beam are journaled in suitable bearings 30 arranged in the frame side-members 7. At the ends of the upper cross-piece 10 are lugs 16 which extend into the front ends of horizontal guideways in the side-members 7. In said guideways are disposed bearing-blocks 17 in which are journaled the ends of the pivot-shaft 3 of the 105 front rocking-beam. A plurality of plate-shims 18 are provided which fit into the guideways adjoining the ends of the bearing-blocks 17, and which may be transposed from one end to the other when it is de- 110

sired to vary the longitudinal position of said bearing-blocks in the guideways. Minor adjustments in the longitudinal position of said bearing-blocks may be made by means 5 of the nuts 12 on the studs 11. The bearing-blocks and the shims 18 are held in transverse position by plates 19 which fit into grooves in the upper and lower edges thereof, as shown in Fig. 6, and which are set 10 cured to the outer sides of the frame.

The ends of the link-shafts 5 and 6 extend out into large rectangular chambers in the frame side-members 7, passing through slots in plates 20 which partially close the inner 15 sides of said chambers. The outer sides of said chambers are normally closed by hinged doors 21, one of which is shown open in Fig. 2. On the ends of the link-shafts are bearing-blocks 22 and 23 which are retained in 20 transverse position on the shafts by collars 24 secured on the shafts at the inner ends of the blocks, and plates 25 secured on the ends of the shafts, as shown in Fig. 6. At each side of the machine the bearing-blocks 25 22 and 23 are connected to each other by a rectangular link 26 formed by a continuous metal strap. The bearing-blocks are disposed in the ends of the link and are held against the same by a spreader- 30 device comprising a threaded rod 27 and end-blocks 28 and 29, the latter being threaded to receive the threaded end of the rod. For adjusting the bearing-blocks to positions closer to each other, the 35 spreader-device is shortened and suitable plate-shims are placed between the sides of the bearing-blocks and the ends of the link. The links 26 receive all tensile stresses between the shafts 5 and 6; while any compressive stresses between said shafts are received by the spreader-devices.

For causing oscillatory movements of the rocking-beams about the axes of the shafts 3 and 4, a toggle - mechanism is provided 45 comprising the front links 31 and rear links 32, the front links being connected with intermediate portions of the shaft 6, the adjacent ends of the front and rear links being connected with a transverse intermediate shaft 33, and the ends of the rear links 32 being connected with a transverse shaft 34 of which the ends are journaled 50 in bearings 35 disposed in the lower rearward end of the frame side-members 7. A vertical reciprocating movement is imparted 55 to the shaft 33 by means of eccentrics 36 from which eccentric-rods 37 extend down and are pivotally connected with said shaft 33. The eccentrics are carried on the main 60 driving shaft 38 which is journaled in bearings 39 on the upper rearward portion of the side-members 7, said shaft being directly above the shaft 33. On the ends of the shaft 38 are fly-wheels 40, which are 65 also employed as driving pulleys and are

connected by belt with a suitable source of power.

Between the adjacent sides of the rocking-beam there is a throat-like space into which the material to be operated upon is fed by gravity from a hopper 41 which is disposed above the upper ends of the beams as shown. The throat is lined with, and the working-faces of the beams thus formed by, renewable members which are secured to the respective rocking-beams, and of which the structure and arrangement are different at different parts of the throat, according to the specific character of the operations performed in the respective parts of the throat. The lowest part of the throat is formed by the rubbing-plates 42, which are made of suitable hard and durable material such as manganese-steel or chromium-steel. The faces or adjoining sides of the rubbing- 80 plates are parallel to each other and quite close together. On the back sides thereof are ribs 43 which fit into channels extending transversely across the lower parts of the rocking-beams. The ribs 43 are slightly 85 shorter than the plates, and are notched at the ends to form laterally extending lugs at the sides thereof adjoining the bottoms of the channels. In the ends of the beams, adjoining the notched ends of the ribs 43, are 90 recesses in which are secured the keeper-plates 44 of which portions extend through the notches in the ends of the ribs, as shown in Fig. 7, and thus retain the plates securely upon the rocking-beams. On each rocking- 95 beam, immediately above the respective rubbing-plates and forming the intermediate side-portions of the throat, there are a series of feed-plates 45 which are disposed alternately in a piled relation with spacing- 100 plates 46, the edges of all the plates engaging the face of the beam, but the plates 46 being narrower than the plates 45 so that there are rectangular transverse open spaces or channels between the edges of the latter 105 adjoining the throat. The upper side-portions of the throat are formed by filler-blocks 47 which are disposed above the feed-plates and spacing-plates, the upper ends of said filler-blocks being in proximity to lugs 110 48 at the upper ends of the rocking-beams. Through said lugs are passed screws 49 which engage the upper ends of the blocks and press the same and the plates 45 and 46 down against shoulders formed on the 115 faces of the beams at the level of the upper edges of the rubbing-plates. Rods 50 extend vertically through coincident openings in the blocks 47 and the plates 45 and 46, to hold said parts in fixed transverse relation to each other. The plates 45 are made of hard material, similar to that of the rubbing-plates 42, but the plates 46 and blocks 47 may be made of softer and less expensive material, such as ordinary cast-iron or cast- 120 125 130

steel. The sides of the upper and intermediate portions of the throat, formed by the blocks 47 and the edges of the plates 45, converge slightly so that the throat is widest at the upper end and becomes gradually narrower toward the lower part, while at the bottom between the rubbing-plates the sides of the throat are substantially parallel.

In Figs. 4 and 5 the rocking-beams are shown in the two extreme positions between which they may be moved by the toggle-mechanism. The positions of the beams shown in Fig. 4 are those assumed when the toggle-links have the greatest deflections above or below a plane passing through the axes of the shafts 6 and 34, and, for convenience in the description, said positions of the beams will be designated as the vertical or normal positions thereof. The positions of the beams shown in Fig. 5 are those assumed when the toggle-links are horizontal, or when the axes of the shafts 6, 33 and 34 all lie in the same plane, and said positions of the beams will be designated as the tilted or inclined positions thereof. The driving eccentrics are so arranged that the toggle-links are moved equal distances above and below the horizontal position, so that during each revolution of the driving shaft the rocking-beams will be moved twice each way between the vertical and the inclined positions thereof.

In Fig. 8 the line A indicates a horizontal plane passing through the axes of the pivot-shafts 3 and 4; the line B indicates a similar plane passing through the axes of the shafts 5 and 6; and the lines C and D indicate planes passing respectively through the axes of the shafts 3 and 5, and through the axes of the shafts 4 and 6; all when the beams are in the normal vertical positions thereof. The working-faces of the rubbing-plates 42 are parallel with the planes C and D, and in Fig. 8 it is assumed for convenience that both sides of the throat are parallel throughout, it being apparent that the movements of the actual working-faces, relatively to each other, will be the same as those of the assumed parallel faces. The rocking-beams are so connected with each other, by the links between the shafts 5 and 6, that the planes A, B, C and D of the shaft-axes form a parallelogram in any position to which the beams may be moved, both beams rotating about their pivotal axes in the same direction and through equal angles. The positions of the planes when the beams are in a tilted or inclined position are indicated by the lines B', C' and D', and the angle m between the lines C and C' is equal to the angle n between the lines D and D'. From Fig. 8 it will be apparent that the working-faces of the beams, or the sides of the throat, will be farthest apart when the beams are in vertical position, or when the

planes C and D are perpendicular to the planes A and B; and in moving to an inclined position the distance between the working-faces, measured perpendicularly thereto, will decrease in a definite mathematical relation to the angle of rotation of the beams about the axes 3 and 4. It will also be apparent that as the beams move toward the inclined position the working-face of the rear beam will move in an upward direction, while the face of the front beam will move in a downward direction; said movements resulting in a rubbing action, or displacement of the working-faces, relatively to each other, in parallel but opposite directions; and that the amount of such displacement will have a definite mathematical relation to the angle of rotation. The first-mentioned movement of the working-faces relatively to each other may be designated as the "closure", while the movement in parallel planes may be designated as the "rub". The actual amounts of closure and rub of the working-faces, in any particular instance, may be expressed by the formulas:

$$\text{Closure} = R \text{ versin } m$$

$$\text{Rub} = R \sin m$$

wherein R is the distance between the pivotal axes, and m is the angle of rotation of the beams about said axes. From the foregoing it will be seen that, as the other factors are equal, the amounts of closure and rub of the working-faces are directly proportional, respectively, to the versed-sines and the sines of the angles of rotation. Now the values of the sines of small angles is very much greater than the values of the versed-sines of the same angles, and consequently, by limiting the rotation of the beams to very small angles it is possible to obtain a considerable rubbing movement of the working-faces, together with an appreciable and definite but very slight closing movement thereof. For example, if the distance between the pivotal axes were 30 inches, and the angle of rotation were 2 degrees, the closure would be $30 \times \text{versin } 2^\circ$, or 30×0.00061 , which is equal to .0183 inches, or slightly less than two-hundredths of an inch of closure; while the rubbing movement would be $30 \times \sin 2^\circ$, or $30 \times .0349$, which is equal to 1.047 inches, or slightly more than one inch of rub. The exact ratio of closure to rub, in this instance, is 1:57. It will now become apparent that, since it is necessary for effective action of the mechanism to have a certain minimum amount of rubbing movement of the working-faces, and as it is desirable to have the ratio of closure to rub very low, it is advantageous to dispose the pivotal axes of the beams as far apart as practicable. By so doing the desired amount of rubbing movement may be attained by rotation of

the beams through a smaller angle than if the pivotal axes were closer together, because in a series of decreasing angles the values of the versed-sines decrease much more rapidly than the values of the sines of the respective angles, so that with the smaller angle of rotation the closure will be less proportionally to the rub. Thus if the pivotal axes were 15 inches apart (instead of 30 inches as in the first example), and it were desired to have the same amount of rub as in the first instance, it would be necessary to rotate the beams through an angle of 4 degrees, at which the closure would be .0366 inches (versin 4° = .00244) instead of .0183 inches, and the ratio of closure to rub would be 1:28 $\frac{1}{2}$ instead of 1:57. In other words, the closure would be twice as great for the same amount of rubbing movement.

Coming now to a consideration of the action of the working-faces of the rocking-beams upon the materials in the throat between them, it should be noted that the materials operated upon are in a granular condition when fed into the throat; the ore, if originally in large masses, being previously crushed or broken into pieces of moderate size such, for instance, that the largest might pass freely down the throat to a position between the plates 45. Now it will be seen that when the throat is filled with material of this character the slight closing movements of the working faces will be insufficient to cause much pressure upon the material in those portions of the throat where the mass of material is of considerable thickness, since the granular mass is capable of being compressed to a slightly smaller bulk by the application of only moderate pressure upon the same. In the lower and narrower parts of the throat the pressure will be greater, since the mass of material is of less thickness, the volume of the interstitial spaces into which the particles may be displaced is less, and yet the reduction of volume per unit of area is the same as in the wider portions of the throat. Consequently, it appears that the pressure upon the material at any particular point will be approximately proportional to the width of the throat at such point, or that the pressure will be greatest between the plates 42, and will be very slight or even inappreciable at the upper part of the throat between the blocks 47. The upper part of the throat, then, serves practically as a continuation of the feed-hopper, to direct the material into the intermediate parts of the throat where the reducing action begins. In the intermediate portions of the throat the material is subject to slight pressure, and is caught by the projecting edges of the plates 45 so that the granular particles are rolled and rubbed against each other by the

rubbing movements of the working-faces. The rectangular transverse channels in the working-faces, between the edge-portions of the plates 45, become filled with particles of the material as shown in Fig. 4, which tend to support said edge-portions of the plates. The material in said channels serves also as a part of the working-faces and minimizes wear and abrasion of the plates. Also, at each oscillation of the beams a portion of the material is carried downward by the plates 45 and thus forced into the space between the rubbing-plates 42. Between the latter plates the material is subject to a greater pressure than before, and the rubbing and abrasion thereof is continued with greater energy; but, owing to the slight movement of closure, the pressure is still insufficient to directly crush the material, so that practically the entire reduction of the material is effected by the rubbing and abrasion thereof and the attrition of its particles upon each other, while the pressure upon the material at any time is merely such as is necessary to make the rubbing action effective.

The plates 42 are so arranged that the lower edge of each will move alternately below and above the lower edge of the other, so that during each movement of the beams one plate tends to scrape the material from the lower portion of the other, and the reduced material is thus constantly discharged from between them.

With respect to the actuating mechanism, it should be noted that the resistance of the rocking-beams to movement thereof becomes greater as the beams approach the extreme tilted or inclined position shown in Fig. 5, since at this time the pressure on the material in the throat is greatest, resulting in the maximum friction of the material upon the working-faces and of the pivot-shafts and links-shafts upon their bearings. But in the movement of the rocking-beams toward the above position the toggle-links approach the intermediate position, at which the links are in horizontal alinement with each other, and where the mechanical advantage of the toggle-mechanism is greatest. Thus the resistance offered by the driven part of the toggle-mechanism during various parts of the cycle of movements is approximately equalized, and the force that must be applied thereto to actuate the same is substantially uniform.

Now, having described my invention, what I claim and desire to secure by Letters Patent is:

1. In an ore pulverizing machine having a pair of rocking means, a shoulder on the inner face of each beam, rubbing plates secured to the beams below the shoulders, a plurality of crushing members supported at the lower ends of the rocking means by said

shoulders and said rubbing plates, and means for clamping the crushing members together and forcing the same into supporting engagement with said shoulders to secure the crushing members against accidental displacement.

5 2. In an ore pulverizing machine having a pair of rocking beams, a shoulder on the inner face of each beam, a plurality of crushing members located above said shoulders, spacing plates located between each adjacent crushing member for spacing the same, said spacing plates being narrower than the crushing members so as to provide channels 10 between the edges of the crushing members, and means for clamping said crushing members and spacing plates together and forcing the same into engagement with said shoulders to securely hold the same on the 15 beams.

20 3. In an ore pulverizing machine having a pair of rocking beams, a shoulder on the inner face of each beam, a plurality of crushing members located above said shoulders, spacing plates narrower than the crushing 25 members, located between said crushing members to space the same and provide

channels between the edges of the crushing members, means for clamping said crushing members and spacing plates together and forcing the same into engagement with said shoulders to securely hold the same on the beams, and rubbing plates secured to said beams below said shoulders.

30 4. In an ore pulverizing machine having a pair of rocking beams, a shoulder on the inner face of each beam, supporting plates secured to said beams below said shoulders, a plurality of crushing members mounted on each beam above the respective shoulders, 35 spacing plates located between the crushing members, and means extending through the respective crushing members and spacing plates to hold the same together and firmly support the same on the respective shoulders.

40 In testimony whereof I have hereunto subscribed my name in the presence of two witnesses.

45 CHAS. O. MICHAELSEN.
